UNITED STATES PATENT OFFICE

158,913

STOCKING

William Tait, Wyomissing, Pa., assignor to Millway Knitting Mills, Inc., Millway, Pa., a corporation of Pennsylvania

Application July 19, 1949, Serial No. 4,003

Term of patent 14 years

(Cl. D47—7)

To all whom it may concern:

Be it known that I, William Tait, a citizen of the United States, residing at Wyomissing, Pa., have invented a new, original, and ornamental Design for a Stocking, of which the following is a specification, reference being had to the accompanying drawing, forming part thereof.

Fig. 1 is a reduced side elevational view of a stocking embodying the design.

Fig. 2 is an enlarged, side elevational view of the lower portion of the stocking shown in Fig. 1.

Fig. 3 is a rear perspective view of the portion of the stocking shown in Fig. 2.

I claim:

The ornamental design for a stocking, as shown.

WILLIAM TAIT.
